No. 714,592.

J. H. MARSH.

Patented Nov. 25, 1902.

PASSENGER AND FREIGHT CONVEYANCE.

(Application filed Aug. 28, 1901. Renewed May 20, 1902.)

(No Model.)

Fig. 1.

UNITED STATES PATENT OFFICE.

JOHN H. MARSH, OF AMANDA, WISCONSIN.

PASSENGER AND FREIGHT CONVEYANCE.

SPECIFICATION forming part of Letters Patent No. 714,592, dated November 25, 1902.

Application filed August 28, 1901. Renewed May 20, 1902. Serial No. 108,199. (No model.)

To all whom it may concern:

Be it known that I, JOHN H. MARSH, a citizen of the United States, residing at and whose post-office address is Amanda, in the county 5 of Oconto and State of Wisconsin, have invented new and useful Improvements in Passenger and Freight Conveyances, of which the following is a specification.

My invention relates to an improved means 10 for conveying passengers and freight across rivers, valleys, and swamps; and the object is to construct a device which will be cheap, durable, efficient, and which will obviate the necessity of bridges and ferry-boats.

Generally the invention consists in the construction and novel combination and arrangement of parts hereinafter fully described, illustrated in the accompanying drawings, and particularly claimed.

Figure 1 of the drawings is a vertical longitudinal sectional view of a device constructed in accordance with my invention, showing the car in side elevation and in dotted lines the manner of passing the cable under the 25 water to permit of the passage of vessels. Fig. 2 is a top plan view of the same. Fig. 3 is a detail view of one of the supports and rollers 2, showing the manner of winding the cable thereon.

Referring now more particularly to the drawings, the numeral 1 designates two longitudinal rows or series of parallel vertical supports, mounted between which are rollers 2 and 3 upon shafts 4 and 5. The supports 1 are 35 of a height sufficient when the device is used as a conveyance over a stream or swamp to support the rollers in the same plane as that of the surfaces of the embankments on either side of the stream or swamp, and when the 40 same is constructed over a navigable river the cable 6 is carried under the water a suitable distance around rollers 2^a and 3^a, said rollers 2^a being mounted between two parallel-arranged horizontal beams 2^b, (one only 45 being shown in dotted lines in Fig. 1,) secured between two of the supports 1, and the rollers 3^a secured between the said supports 1, thereby providing ample space for the passage of vessels.

The endless cable 6 extends between the two wharves or abutments 7 and 8, located upon opposite sides of the river or stream,

which carry end-supporting rollers and corresponding to those denoted 2 and 3 on the intermediate supports 1. The upper stretch 55 of the cable is successively wound one or more times about the rollers 2, while its lower stretch rests upon and travels over the lower rollers 3, which serve as idlers. Arranged beneath or adjacent to the wharf or abutment 6c 7 is an engine 9, which communicates motion to a drum 10, around which the adjacent loop of the cable passes and by which said cable is driven. Through the medium of the engine 9 and the cable 6 motion is imparted to 65 the rollers 2, upon which rides the car 11, whereby the latter is propelled.

Mounted upon the supports 1 are vertical shafts 12, carrying antifriction or guide rollers 13, which guide and maintain the car 11 in 70 proper position upon the rollers 2 and obviate all liability of the car becoming derailed or sliding laterally off said rollers.

The car 11 consists of a flat body portion 14, which is approximately elliptical in form. 75 The peculiar construction of the body portion permits the car to be guided between the antifriction or guide rollers, thereby obviating any liability of the car becoming derailed or sliding laterally off the rollers 2. The car 80 has a cabin 15 to accommodate the passengers, and the space not occupied by the cabin is utilized to carry wagons and freight. This particular disposition of the top of the body portion is immaterial, as it may be fitted up 85 in any improved style to adapt it to any particular use to which it may be put. The flat body portion or bottom of the car forms a friction-surface resting on the upper stretch 90 of the cable and the rollers 2, whereby when said cable and rollers are put in motion the car is driven.

In operation it will be readily seen that when motion is imparted to the cable and rollers 2 by means of the engine 9 the car 11 95 will be propelled in one direction or the other, according to the direction of rotation of the drum 10, whereby passengers and freight may be transported across a river, marsh, or stream without liability of danger.

From the foregoing description, taken in connection with the accompanying drawings, the construction, mode of operation, and advantages of the invention will be readily un-

derstood, and it will be seen that a simple, cheap, durable, and effective device is provided.

While I have specifically described what appears to me at this time to be the very best means of accomplishing the desired result, I would have it understood that I do not limit myself to the exact construction shown, but reserve the right to make such slight changes and alterations as would properly come within the scope of my invention without departing from the spirit thereof.

Having thus fully described my invention, what I claim as new, and desire to secure by Letters Patent, is—

15. 1. In an apparatus of the character described the combination of a car provided with an elliptical-shaped bottom, a track on which the car is propelled, and antifriction-rollers engaging the sides of the ellipse to prevent lateral displacement.
20. 2. In a device of the character described, the combination of suitable supports, upper and lower rollers mounted between said supports, a car carried by said rollers, an endless cable carried by said rollers for imparting motion to the rollers to propel the car, and means to actuate the cable.
25. 3. In a device of the character described, the combination with two longitudinal rows or series of parallel vertical supports, rollers mounted between said supports, a car carried by said rollers, means for imparting motion to the rollers to propel the car, antifriction-rollers arranged on top of said supports to guide the car laterally.
30. 4. In a device of the character described,

the combination with two longitudinal rows or series of parallel vertical supports, shafts mounted between said supports, rollers journaled on said shafts, a car carried by said rollers, a cable imparting motion to said rollers to propel said car, and vertical shafts mounted upon said supports and carrying antifriction-rollers to guide the car laterally. 40 45

5. In a device of the character described, the combination with two longitudinal rows or series of parallel vertical supports, upper and lower sets of shafts carried between said supports, rollers journaled on said shafts, an 50 endless cable having its lower stretch resting upon and traveling over the lower rollers and its upper stretch wound successively around the upper rollers, a car mounted upon the upper rollers, and means for driving the cable, 55 substantially as described.

6. In a device of the character described, the combination of two longitudinal rows or series of parallel supports, rollers journaled between the supports, an intermediate set of 60 rollers carried by the supports and normally submerged, a cable passing over the first-named rollers and under the intermediate rollers to permit the passage of vessels between the supports, and a car normally resting on the first-named rollers and adapted to be propelled by the cable.

In testimony whereof I affix my signature in presence of two witnesses.

JOHN H. MARSH.
